UNITED STATES PATENT OFFICE.

CHARLES EDWARD HAVILAND, OF LIMOGES, FRANCE.

DESIGN FOR A CUP.

SPECIFICATION forming part of Design No. 21,686, dated July 5, 1892.

Application filed June 7, 1892. Serial No. 435,897. Term of patent 14 years.

To all whom it may concern:

Be it known that I, CHARLES EDWARD HAVILAND, a citizen of the United States, residing at the city of Limoges, in the Republic of France, have invented and produced a new and original Design for a Cup and other Articles, of which the following is a specification, reference being had to the accompanying drawings, forming part thereof, and in

10 which—

Figure 1 is a side view of a cup bearing my design; Fig. 2, a top view of same, and Fig. 3 a detached section of a part of same on the dotted line 3 3 of Fig. 2.

15 The leading features of my design consist of the shape of the body of the cup and the ornamental configurations thereon, as shown in Figs. 1 and 2, without regard to the handles A A, which form no absolutely-essential 20 part of either the cup or the design. The body of the cup consists of the scalloped sections B, which taper downward and inward to the ornamental base C, composed of scal-

loped sections D, in line with said sections B. At the connecting-line of the base C with the 25 body of the cup is the encircling band E, composed of closely-arranged uniform short vertical bars F, as shown in Fig. 1. The upper edge of the body of the cup bears the beading G, and below this is the scalloped ornamental configuration H, shown as though 30 looped or held by the rosettes I, producing thereby a lambrequin effect. Between the edge beading G and the scalloped configuration H is the field J, covered with short vertical bars K and bearing the line of beads L.

35 What I claim is—

The design for a cup or other article, substantially as shown and described.

Signed at the city of Limoges, in the Republic of France, this 25th day of May, 1892.

CHARLES EDWARD HAVILAND.
